UNITED STATES PATENT OFFICE.

FRANCIS S. JONES, OF WEST NEW BRIGHTON, NEW YORK, ASSIGNOR OF ONE-THIRD TO MARY E. JONES AND ONE-THIRD TO LEON W. JONES, BOTH OF WEST NEW BRIGHTON, NEW YORK.

PRESSER-FOOT ATTACHMENT.

Application filed July 30, 1923. Serial No. 654,695.

To all whom it may concern:

Be it known that I, FRANCIS S. JONES, a citizen of the United States, residing at West New Brighton, Staten Island, in the county of Richmond and State of New York, have invented new and useful Improvements in Presser-Foot Attachments, of which the following is a specification.

This invention relates to a device for attachment to the presser-foot of a sewing machine and has for its primary object the provision of a means for guiding the presser foot in a plane parallel to the marginal edge of the work; whereby the stitching is evenly spaced from said marginal edge.

Another object of the invention is the provision of a device which is detachably connected with a presser-foot so that the same may be readily removed and another substituted therefor when it is desired to change the distance between the marginal edge of the work and the stitching.

A further object of the invention is to provide a device which is yieldable in order to adapt itself to various thicknesses of materials.

A still further object of the invention is to provide a device of the type mentioned which is stamped from a single piece of material thereby rendering the same simple in construction, cheap of manufacture and highly efficient for the purpose intended.

With these and other objects in view, the invention resides in the certain novel construction, combination and arrangement of parts, the essential features of which are hereinafter fully described in the specification, are particularly pointed out in the claim, and are illustrated in the accompanying drawing, in which:

Figure 1 is a side elevation of a presser foot with my invention applied thereto.

Figure 2 is a transverse sectional view on the line 2-2 of Figure 1.

Figure 3 is a horizontal sectional view on the line 3-3 of Figure 1.

Figure 4 is a detail sectional view on the line 4-4 of Figure 1.

Figure 5 is a perspective view of my invention per se.

It is my aim to produce a device which will permit accurate and uniform stitching by means of a sewing machine, especially by beginners of this particular work while

operating at a high rate of speed. Also the invention reduces the amount of eye-strain usually required in stitching, for the reason that the operator is not compelled to constantly keep his eyes on the work, but may feed the work through the machine by "feeling."

Referring more particularly to the drawing, the reference numeral 10 designates a presser-foot of the usual well-known construction for use in connection with single needle sewing machines. The presser-foot includes a shank 11, and a pair of spaced toes 12 and 13 in the form of furcations. The toe 12 is shorter than the toe 13, and it is to this toe that a portion of my device is attached.

My device is shown at 14 in its entirety and the same is shown as stamped from a single piece of flat material, coiled at one end to provide a horizontal portion 15 having 75 formed thereon a finger 16 for insertion in a slot 17 provided in the front wall of the shank 11. The free end of the material is bent downward to form a hook 18 for co-action with a lug 19 extending outwardly 80 from the side of the shank 11. The structure so far described serves as an attaching means for connecting the device to the presser-foot. The other end of the device is adapted to co-act with the small toe 12 of 85 the presser-foot as clearly shown in Figures 1 to 3 of the drawing. This end of the material is provided with a pair of downwardly bent walls 20 and 21, the wall 20 being slightly greater than the height of the 90 presser-foot 10, and adapted to straddle the toe 12 so as to dispose the wall 20 in close contact with the inside of the toe and within the space between the toes 12 and 13. The wall 20 is longer than the wall 21 and is 95 curved upward at its front as at 22 so as to ride smoothly over the work and prevent wrinkling of the goods. The wall 20 acts as a guide and is adapted to co-act with the edge 23 of a piece of work 24 so as to permit

the line of stitching 25 to be parallel with the edge 23. It will be seen that when the device is attached in the manner described, the guide wall 20 is permitted vertical movement against the tension of the coiled portion of the material so as to adapt itself to materials of various thicknesses. This feature being clearly shown in Figure 2 of

the drawing. The thickness of the wall 20 acts as a gage for spacing the stitching 25 from the edge 23. In other words when it is desired to space the stitching further away from the side edge, it would be necessary to substitute a device whose wall 20 was of a lesser thickness so as to dispose the needle slot 26 further away from the edge 23, and if a smaller space between the stitching 10 and the edge is desired, it would be necessary to substitute a device whose wall 20 was of greater thickness so as to dispose the needle slot 26 in closer proximity to the edge 23. I have found it convenient when a relatively 15 wide margin is desired to form the wall 20 on the opposite side of the toe and the wall 21 on the inside of the toe, or in other words, reverse the walls 20 and 21.

From the foregoing it is believed that 20 the construction and manner of operation has been clearly set forth and a further description of the same is not deemed necessary. It will be understood that by guiding the presser-foot in a line parallel to the 25 marginal edge of a piece of work, an accurate and neat job of stitching will be produced, and the necessity of constantly straining the eyes with an endeavor to make sure

that the stitching is being made uniformly straight is dispensed with. 30

While I have shown and described what is deemed the best embodiment of my invention I wish it to be understood that changes, alterations and modifications as come within the scope of the appended claim may be 35 resorted to when desired.

What is claimed as new is:

An attachment for a presser foot of a sewing machine including a longitudinally curved resilient strip, a laterally extending 40 base carried thereby at one end and adapted to be received in a slot provided in the shank of the presser foot, rounded forwardly projecting guides carried by the opposite ends of the strip and adapted to slide along the longitudinal edge of the work being stitched, and a vertically extending wall carried by said end of the resilient strip and disposed in opposed relation to the guide, the guide being disposed upon one side of 50 the presser foot and the wall being disposed upon the other side and both serving to hold the strip against lateral movement. 45

In testimony whereof I have affixed my signature.

FRANCIS S. JONES.
